UNITED STATES PATENT OFFICE.

THOMAS PERKINS, OF LAFOURCHE CROSSING, LOUISIANA.

SHARPENING-MACHINE.

1,146,513.

Specification of Letters Patent.

Patented July 13, 1915.

Application filed April 17, 1915. Serial No. 22,125.

To all whom it may concern:

Be it known that I, THOMAS PERKINS, a citizen of the United States, residing at Lafourche Crossing, in the parish of Lafourche and State of Louisiana, have invented a new and useful Sharpening-Machine, of which the following is a specification.

This invention relates to sharpening machines especially designed for use in sharpening the blades of clippers such as used by barbers.

One of the objects of the invention is to provide a machine of this character which is simple, durable and compact, will not readily get out of order, and which has novel means for holding the blade in position upon the hone during the operation of the machine.

20 With the foregoing and other objects in view which will appear as the description proceeds, the invention resides in the combination and arrangement of parts and in the details of construction hereinafter described 25 and claimed, it being understood that changes in the precise embodiment of the invention herein disclosed, can be made within the scope of what is claimed, without departing from the spirit of the invention.

30 In the accompanying drawings the preferred form of the invention has been shown.

In said drawings:—Figure 1 is a plan view of the machine, the cover being shown 35 open and broken away. Fig. 2 is a section on line A—B Fig. 1, the cover being shown in closed position. Fig. 3 is a section on line C—D Fig. 2.

Referring to the figures by characters of 40 reference 1 designates a box-like housing which may be provided with any suitable means, such as tongues 2, for securing it upon a table or other supporting structure, each of these tongues having an eye 3 for 45 the reception of a fastening screw. Arranged longitudinally within the upper portion of the housing 1 are parallel rods 4 forming a track which is slidably engaged by ears 5 extending laterally from the end 50 portions of a holder 6 in which is mounted a hone 7. An extension 8 is formed upon the bottom of the holder and a spring 9 is secured at one end to this extension and at its other end to one end of the housing 1, 55 this spring serving to maintain the holder normally adjacent one end of the housing.

A hanger 10 extends downwardly from the extension and is connected by a pitman 11 to a crank 12 provided adjacent the center of a transverse shaft 13. This shaft is journaled within the sides of the housing 1 and has any suitable means, such as a crank arm 14, whereby it can be rotated readily.

Bearing downwardly on the hone 7 is a backing plate 15 provided, at each corner, 60 with a hook 16. Extending from each hook is a coiled spring 17, these springs being secured to the housing 1 close to each corner thereof. In other words, the springs extend along diverging lines and it will be noted, 65 furthermore, by referring to Figs. 2 and 3, that these springs are inclined downwardly away from the backing plate 15 so that they not only serve to hold said plate constantly centered upon the hone 7, but also pull it 70 downwardly onto the hone. The backing plate 15 can be removed readily whenever desired by unhooking the springs 17 from the hooks 16. Openings 18 are formed in the plate 15 near the center thereof and receive plugs 19.

In using the machine herein described, two of the springs 17 are disconnected from the plate 15 and said plate lifted off of the hone. The blade to be sharpened is then 85 placed on the hone and the plugs 19 are inserted into the openings 18 and into the corresponding holes in the blade to be sharpened after which the springs 17 are again placed in position and all of the springs will 90 coöperate to hold the blade pressed yielding onto the hone. By rotating shaft 13, the hone will be reciprocated under the yielding held blade and this reciprocation can be continued as long as desired.

When the machine is not in use the cover 20 can be closed, as shown in Figs. 2 and 3.

What is claimed is:—

1. The combination with parallel rods, of a holder mounted for reciprocation thereon, a hone carried thereby, means for reciprocating the holder, a backing plate, and springs diverging outwardly and downwardly from the backing plate for holding the plate yieldingly pressed upon the hone 100 and for holding it yieldingly against movement with the hone.

2. The combination with parallel rods, of a holder mounted for reciprocation thereon, a hone carried thereby, means for reciprocating the holder, a backing plate, springs diverging outwardly and downwardly from

the backing plate for holding the plate yieldingly pressed upon the hone and for holding it yieldingly against movement with the hone, and means detachably connected to the backing plate for holding a blade between the plate and the hone.

3. The combination with a housing and guide rods therein, of a holder mounted to reciprocate upon the rods, a crank shaft, means for transmitting motion from the crank shaft to the holder to reciprocate the holder, a hone upon the holder, yielding means connecting the holder to one end of the housing, a backing plate, downwardly and outwardly diverging springs connect-

ing said backing plate to the housing and constituting means for holding the plate pressed yieldingly against the hone and to hold the plate yieldingly against movement with the hone, and means carried by the 20 backing plate for engaging a blade to hold it between the plate and hone.

In testimony that I claim the foregoing as my own, I have hereto affixed my signature in the presence of two witnesses.

THOMAS PERKINS.
